UNITED STATES PATENT OFFICE.

HUGO LORANT, DUSSELDORF, GERMANY, ASSIGNOR TO SCHLOEMANN AKTIENGESELLSCHAFT, OF DUSSELDORF, GERMANY, A CORPORATION OF GERMANY.

METAL TUBE AND BAR PRESS.

Application filed May 20, 1927. Serial No. 192,821, and in Germany July 10, 1926.

My invention relates to presses for producing metal tubes, or bars of various shapes and cross-sections. In presses of this kind, the cylinder for the press-plunger and the standard for the ingot receiver are mounted on the same base-plate so as to insure perfect alinement. It has been found, however, that where hot ingots are placed in the press, the ingot receiver and the holder therefor, because of the great heat to which they are subjected will expand, and consequently, the alinement of the receiver and the cylinder for the press-plunger is disturbed, or in other words, the central axis of the ingot receiver becomes displaced relatively to the central axis of the cylinder for the press-plunger. This results, of course, in an uneven thickness of the walls of the tubes, requiring subsequent treatment of the tubes in drawing machines, which involves considerable expenditure of time and money. To obviate this defect is the object of the present invention, according to which the ingot receiver or the holder therefor rests on special supports, which remain unaffected by the heat of the hot ingot, so that the central axis of the ingot receiver remains in true line with the central axis of the cylinder for the press-plunger and of the latter, no matter how great the heat imparted to the ingot receiver. The supports which may be air- or water-cooled, are mounted on the same base-plate with the cylinder for the press-plunger.

In the appended drawing, on which I have shown an embodiment of my invention by way of illustration, Fig. 1 is a central vertical section through a well-known press for making metal tubes not embodying the present invention, Fig. 2 being a cross-section of the same along line 2—2 in Fig. 1; Figs. 3 and 4 are similar views as Figs. 1 and 2 showing a press embodying the present invention, Fig. 4 being a section along line 4—4 in Fig. 3.

In all the figures, the same reference letters have been used to designate identical parts.

The press, as shown in the drawing, comprises a cylinder *a*, the press-plunger *b* in said cylinder, the ram *c*, carrying the perforating mandrel *c'*, the holder *d*, the ingot receiver *e*, the matrix *f* and the common base-plate *g*.

In the press shown in Figs. 1 and 2, the cylinder *a* and holder *d* are mounted on the base-plate *g*. When a hot ingot is placed in the ingot receiver *e*, the latter and thereby also the holder *d* become very hot, with the result that the lower portion *i* of holder *d* (Fig. 2) becomes expanded by the heat and the horizontal central plane of the ingot receiver *e* becomes displaced relative to the horizontal central plane of the press-plunger *b*.

Now, in the press shown in Figs. 3 and 4, the holder *d* for the ingot receiver is not directly mounted on the base-plate *g*, but rests on special supports *h* which engage the holder *d* at or substantially at its horizontal central plane and are mounted on the base-plate *g*. These supports *h* which, if desired, may be air- or water-cooled, remain practically unaffected by the heat imparted by the hot ingot to the holder *d* and consequently will not become expanded so that the central axis of the ingot receiver will always remain in exact alinement with the central axis of the press-plunger, no matter how high the temperature of the ingot receiver *e* may rise.

In place of the supports *h* also a frame may be used in which the holder *d* is suspended, and it is obvious that other modifications may be made without any departure from the essence of the present invention.

I claim:

1. In a horizontal metal tube extrusion press, the combination with the base-plate, of an hydraulic cylinder mounted thereon, a press-plunger in said cylinder, an ingot receiver, and means unaffected by the heat imparted to said ingot receiver for supporting the same in a horizontal central plane so as to permit free expansion in all directions without displacement of the central axis of said receiver.

2. In a horizontal metal tube extrusion press, the combination with the base-plate, of an hydraulic cylinder mounted thereon, a press-plunger in said cylinder, an ingot receiver, a holder therefor, and supporting means for said holder unaffected by the heat imparted to said receiver so as to support the same in a horizontal central plane permitting free expansion in all directions with-

out displacement of the central axis of said receiver.

3. In a horizontal metal tube extrusion press, the combination with the base-plate, 5 of an hydraulic cylinder mounted thereon, a press-plunger in said cylinder, an ingot-receiver, a holder therefor, and two supports

unaffected by the heat imparted to said ingot-receiver for supporting the same in a horizontal central plane without displacement of the central axis of said receiver. 10

In testimony whereof I affix my signature.

HUGO LORANT.
